DOOR HOOK MOUNTING

George R. Bellah, West Arcadia, Calif.

Application November 15, 1937, Serial No. 174,516

2 Claims. (Cl. 292—101)

My invention relates to a mounting for hooks utilized in securing, in closed positions, doors, gates or any other swinging structure wherein the hook is mounted to swing vertically on a horizontal axis, and the principal objects of my invention are to provide a relatively simple, practical and inexpensive one-piece mounting for hooks wherein the mounting is constructed so that the hook is pivotally mounted in said mounting so as to swing only in a vertical plane, and the mounting being constructed so as to limit the swinging movement of the hook in both directions so that it may always be conveniently manipulated so as to engage the screw-eye or staple that is seated on a fixed portion of the structure with which the door or other swinging closure is associated.

Further objects of my invention are, to generally improve upon and simplify the construction of the existing door hook mountings, further, to provide a mounting that is formed in a single piece, preferably formed from sheet metal or wire, in order that it may be produced at low cost or manufacture, and further to provide a hook mounting of the character referred to that is of strong, durable construction so that it will readily withstand rough usage to which it may be subjected.

A further object of my invention is, to provide a hook mounting that is reversible in order that it may be readily applied to both right and lefthand swinging doors or like closures, and further to construct the mounting so that it may be positioned on a screen door or the like, so that the hook associated with the mounting will engage in a screw-eye or staple that is seated in the door casing immediately behind the stop for the screen door.

With the foregoing and other objects in view my invention consists in certain novel features of construction and arrangements of parts that will be hereinafter more fully described and claimed and illustrated in the accompanying drawing in which:

45 Fig. 1 is an elevational view of the mounting positioned on a door wherein the hinges are mounted on the righthand edge of the door.

Fig. 2 is a top plan view of the mounting and the hook that is associated therewith.

50 Fig. 3 is an elevational view of the mounting positioned on a door having its hinges on the lefthand vertical edge.

Fig. 4 is a plan view of the mounting and hook associated therewith applied to a screen door so 55 that the free end of the hook will engage the

staple or other keeper behind the stop for the free edge of the door.

Fig. 5 is a detail section taken on the line 5—5 of Fig. 1.

Fig. 6 is an elevational view of a modified construction wherein the hook mounting is formed from a single piece of wire.

Fig. 7 is a plan view of a modified form of the mounting seen in Fig. 6.

Fig. 8 is a view looking against the under side 10 of the modified form of the mounting and the hook associated therewith.

Referring by numerals to the accompanying drawing, and particularly to the construction illustrated in Figs. 1 to 5 inclusive, 10 designates 15 a door or other swinging structure, the free edge of which swings against a frame or casing 11, and seated in the face of the latter is a screw-eye or staple 12 that is adapted to receive the free end of the hook that secures the door in closed 20 position.

The mounting for the hook is formed from a single piece of metal, the main portion of which is bent double to form spaced parallel walls 13 and 14, connected at one end by a half loop 15. Formed integral with the free edge of the plate 14 that is positioned against the outer face of the door or other swinging structure is a vertically disposed flange 16 that projects at right angles from the plate 14 of the mounting which 30 is applied to the door. This flange 16 engages directly against the door 10 as illustrated in Fig. 2.

Formed through the plates 13 and 14 adjacent their free edges are aligned apertures 17, one pair of apertures being disposed above the other, and when the mounting is applied to the door, a screw 18 is inserted through the lower pair of apertures and said screw is seated in the door 10 so as to secure the mounting thereto.

Formed through the plates 13 and 14 adjacent the ends that are connected by half loop 15 are aligned apertures 19, and passing through and into the door to secure the mounting thereto is a screw 20.

The hook 21, which is preferably formed from heavy wire, is provided on one end with a loop 22 through which screw 20 passes, and a substantial portion of the body of the hook 21 adjacent the loop 22 is normally positioned between the plates 13 and 14 of the mounting. At the free end of the hook a portion of the wire from which the same is constructed is bent at right angles upwardly, to form a short leg 23 and from the upper end of said short leg the wire is bent 50 55

downwardly parallel with the leg 23 to form a leg 24 that is approximately twice the length of leg 23.

- Thus the hook 21 is provided on its free end with two members, one extending upwardly from the body of the hook and the other extending downwardly, and which construction enables the hook to engage the screweyes or staples on the casings of both right and left hand hung doors.
- 10 The space between the plates 13 and 14 is slightly wider than the diameter of the wire used in the construction of the hook 21, and thus said hook must necessarily swing in a vertical plane with the screw 20 as the axis of movement and as a result, the hook, when disengaged from the screw-eye or staple, is always in position to be swung downward or swung upward and then downward so as to engage the screw-eye or staple and secure the door in closed position.
- 20 The upper edge of the half loop 15 that connects the rear ends of walls 12 and 13 provides a stop to limit the upward swinging movement of the hook and the screw 18 that is positioned in the lower pair of apertures 17 provides a stop to limit the downward swinging movement of the hook. (See dotted lines Fig. 1.)

When the mounting is applied to a door, for instance a screen door D that swings against a stop S, the mounting is positioned on the door a short distance from the free edge thereof with the end of the plate 14 adjacent the half loop 15 and the end of flange 16 in contact with the door. Due to the flange 16, the mounting occupies an inclined position relative to the face 35 of the door, and thus the free end of the hook 21 will conveniently engage a screw-eye or staple 12a that is seated in the door casing immediately behind the stop S (see Fig. 4).

In the modified construction illustrated in Figs. 40 6, 7 and 8, the mounting is formed in a single piece from wire and one end 24 of the piece of wire utilized in constructing the mounting is threaded, in order that it may be screwed into a fixed structure such as a door casing, post or 45 the like. From member 24, the wire is bent at right angles to form a short leg 25, and from the end of said leg the wire is bent to form a half loop 26 and the wire from said half loop is extended a short distance to form a leg 27 that 50 occupies a position approximately parallel with and spaced apart from the leg 25. From said leg 27, the wire is bent upward to form a half loop 28 that passes half around the threaded end portion 24, and from said half loop 28 the 55 wire is extended in a plane above and substantially parallel with leg 27, to form a leg 29 that lies in the same vertical plane with and directly above leg 27.

From the end of leg 29 the wire is bent to form 60 a half loop 30 and from the latter the wire is extended to form a leg 31 that is positioned directly in front of and spaced apart from the leg 29 and directly above leg 25. Leg 31 terminates in a downwardly bent portion 32 that overlies the

end of leg 25 at the point where the same joins the threaded portion 24. The legs 25, 27, 29 and 31 will occupy planes that are slightly inclined with respect to the horizontal with the threaded end portion 24 slightly below the half loop 26. 5

A hook 33 of conventional shape has the loop 34 on its rear end engaged with the half loop 26 between the legs 25 and 27 and the adjacent portion of the hook occupies a position between the parallel legs 25 and 27. The free end of hook 33 10 is adapted to engage a screw-eye or staple 35 that is seated in the door casing, post or other structure against which the door or gate closes.

Thus the hook 33 is held in the mounting so as to swing only in a vertical plane, and the member 24 that is seated in the door casing or post provides a stop to limit the downward swinging movement of the hook and the half loop 30 that connects the parallel members 29 and 31 15 limits the upward swinging movement of the 20 hook.

Thus it will be seen that I have provided a hook mounting that is relatively simple in construction, inexpensive of manufacture and very effective in performing the functions for which it 25 is intended.

The mounting is adapted to be applied to both right and left hand hung doors and other swinging structures, and the hook that is associated with the mounting is held so as to swing only in 30 a vertical plane so that it may be more conveniently engaged in the screw-eye or staple that is seated in the fixed member against which the free edge of the door closes.

It will be understood that minor changes in the 35 size, form and construction of the various parts of my improved door hook mounting may be made and substituted for those herein shown and described without departing from the spirit of my invention, the scope of which is set forth 40 in the appended claims.

I claim as my invention:

1. A door hook mounting comprising a pair of spaced parallel plates connected to each other at one end, a screw passing through said plates 45 adjacent their connected ends, a hook pivotally mounted on said screw between said plates, there being apertures formed through said plates adjacent the ends opposite their connected ends in a horizontal plane slightly below the horizontal 50 plane occupied by said screw and a screw passing through said last mentioned apertures.

2. A door hook mounting formed from a single piece of material bent double to form a pair of substantially parallel spaced vertically disposed walls, said walls being provided adjacent their connected ends with apertures for the reception of a fastening device, said walls being provided adjacent their free ends with apertures for the reception of a fastening device and said last 60 mentioned apertures being located slightly below the horizontal plane occupied by the first mentioned pair of apertures.

GEORGE R. BELLAH.
